SUPPLY AND WASTE FITTING

Carl J. Kohler, Kohler, Wis.

Application May 17, 1935, Serial No. 22,023

14 Claims. (Cl. 4—200)

My invention relates to improvements in waste fittings of a type adapted for use in connection with a plumbing fixture, and the objects of my invention are: first, to provide a construction 5 wherein the waste plug is readily removable without the use of tools or the necessity of loosening or removing any other parts of the assembly and, second, to provide a compact and convenient arrangement of the various parts of said fitting 10 whereby the fitting in effect forms an integral part of the plumbing fixture. Other objects and advantages will be apparent from the following disclosure.

I attain these objects by the mechanism illustrated in the accompanying drawings, in which Figure 1 is a plan view of the waste mechanism partly in section along the lines 1—1 of Figure 2; Figure 2, a side elevation thereof, partly in section along the lines 2—2 of Figure 1; Figure 3, a 20 side view of the waste plug; Figure 4, a plan view similar to Figure 1 but showing the operating mechanism in a different position of adjustment; and Figure 5, a side view, partly in section, of a lavatory with the fitting attached.

25 Although the invention is herein illustrated and described with particular reference to its use in connection with a lavatory, it will be apparent to those skilled in the art that certain features thereof are adaptable, without invention, 30 for use in connection with other fixtures such as bath tubs, for example, hence all mention of the lavatory herein is for the purpose of demonstrating the utility of the invention and is not intended to limit the application of the invention to use 35 solely in connection with lavatories.

In the drawings, the numeral 1 indicates a lavatory, formed with an overflow housing 2, and a waste housing 3. A valve seat 4 is seated on the lavatory, extends through the waste housing 3 and is threaded at 5 for connection to the nut 6. A 40 compressible gasket 7 is interposed between the nut 6 and the waste housing 3 to prevent leakage. The nut 6 is provided with the internally threaded skirt 8 for threaded attachment to the drain pipe 9, which is adapted for attachment to the conventional trap, not shown. The valve seat 4 is provided with an aperture 10 providing communication between the overflow housing 2 and the interior of said valve seat. A valve or waste plug 11 is adapted to seat on the valve seat 4 and is provided with the apertures 12 providing communication, through aperture 10, between the interior of said waste plug and the overflow housing 2.

The waste housing 3 is formed with the bore 13 which provides communication between the

interior and exterior of said housing and is constricted at 14 to form a shoulder or abutment.

An operating lever, indicated generally at 15, comprises a centrally located spherical portion 16, an extremity 17 extending through the waste 5 housing 3 and engaging the waste plug 11 in a manner hereinafter more particularly described, and an extremity 18 extending outwardly from the waste housing and adapted to engage a lift rod as hereinafter described.

The spherical portion 16 abuts the packing 19 which is interposed between the spherical portion 16 and the shoulder 14. It will be understood that the portion 16, instead of being completely spherical as shown, may be semi-spherical 15 or of other configuration having an accurate surface bearing on the packing 19.

The waste housing 3 is formed with a slot 20 which, as shown, is somewhat wider than the bore 13 and extends therethrough to a point somewhat 20 above said bore. This slot, like the bore 13, may be formed by the use of suitable cores during the casting or forming of the waste housing 3.

A nut 21, preferably square in configuration, is inserted in said slot so that its bore registers 25 with the bore 13. An externally threaded, tubular plug 22 extends through the bore 13 and is threaded in the nut 21. The plug 22 abuts the packing 14 and compresses it, thus insuring against leakage between the shoulder 14 and the 30 packing. The plug 22 is provided with the aperture through which the extremity 18 of the operating lever extends.

A coil spring 24 is positioned within the plug 22 and at one extremity engages the head of the 35 plug and at the other extremity engages the follower 25 which, in turn, engages the spherical portion 16 of the operating lever. Thus the spring 24 acts to hold the spherical portion in firm engagement with the packing 19 preventing leakage and maintaining a proper position for operation.

It will thus be seen that the various parts form a compact and convenient assembly which is virtually a part of the fixture and requires no drilling, tapping or machining of the fixture to apply.

The fixture is provided a discharge spout 26 connected to a source of water supply such as a supply fitting 27. The flow of water through said supply fitting is controlled by suitable valves, not 50 shown. The discharge spout 26 is provided with the escutcheon 27 which overlaps the fixture and may be, as shown, integral with the spout or separate therefrom and attached thereto as desired.

An operating rod 28, provided with a knob han- 55

dle, is slidably mounted in the escutcheon 27 and has pivotal connection at 29 to the bell crank lever 30. The bell crank lever 30 is pivotally connected at 31 to the yoke 32, integrally formed 5 or otherwise attached to the supply fitting 30. A lift rod 33 has flexible connection at 34 to the operating lever 15 and is pivotally connected at 35 to the bell crank lever 30.

Thus the waste plug 11 may be raised from 10 its seat by pushing the operating rod 28 inwardly and seated by pulling the operating rod outwardly. It will be noted that the waste plug operating mechanism is integrated with the supply mechanism and that the whole forms a compact and convenient assembly.

An important feature of the invention is the provision of novel means whereby the waste plug 11 may be removed without the use of tools, thus rendering the drain accessible for cleaning.

20 In the normal operable position, shown in Figures 4 and 5, the extremity 17 of the operating rod 15 extends through the waste housing 3 and through the aperture 36 in the waste plug 11. It will be noted that, in this position, the operating rod 15 is in line with the centers both 25 of the waste plug 11 and the spherical portion 16 regardless of whether the waste plug 11 is in a raised or seated position and that the operating rod 15 operates in a vertical plane, passing 30 through the center of the bore 13. It will also be noted that the construction is such that the operating rod 15 naturally tends to assume this centered position upon actuation of the lift rod 33.

35 The aperture 36 is positioned in a groove or slot 37 extending from the bottom of the waste plug 11 to the aperture 36. The groove 37 may be V-shaped or of any other suitable configuration; however, I prefer the configuration shown 40 in the drawings in which the sides of the groove, if extended, would form chords with the circumference of the waste plug, the side 38 being of greater length and of more gradual pitch than the side 39.

45 Instead of being provided with the aperture 36, the groove 37 may, if desired, be made deep enough to receive the operating rod 15.

In order to remove the waste plug 11 it is necessary only to raise the plug to its lifted position and turn it clockwise to the position shown 50 in Figures 1 and 2. In this position it is no longer engaged by the operating lever 15 and can be lifted out directly. It may be replaced by the reverse action or the plug 11 may be simply replaced and the operating rod 28 actuated when, 55 due to the tendency of the operating lever 15 to center itself as described above, the plug 11 returns to the position shown in Figures 4 and 5, in which position it is locked against removal,

60 and also, the side 39 acting as a stop against further rotation in the locking direction. It will be obvious that, if desired, the construction may be such that the waste plug 11 is removable upon a counter-clockwise turn instead of a clockwise turn.

65 It will thus be seen that I have provided a construction in which the waste plug is normally locked against removal, but may be removed by a simple turn thereof without the necessity of using tools of any kind or loosening or disturbing any other parts of the assembly. The cleaning of the drain connection is thus facilitated, since it is not necessary to remove the drain pipe or trap when the drain becomes 70 clogged or is in need of cleaning, since these

parts are readily accessible upon removal of the waste plug.

It will be obvious to those skilled in the art that numerous changes may be made in the specific construction illustrated and described 5 without departing from the spirit of my invention, and I therefore do not limit myself to the exact construction herein disclosed but claim all equivalents and modifications thereof within the spirit of my invention and the scope of the 10 appended claims.

I claim:

1. A waste fitting comprising a waste plug valve, means for operating said valve and connecting means on said waste plug valve, said 15 connecting means engaging said operating means to operatively connect said waste plug and said operating means and to lock said waste plug valve against removal and against further rotation upon turning of said waste plug valve in 20 one direction and to disengage said connecting means upon turning of said waste plug valve in the opposite direction.

2. A waste fitting comprising a waste plug valve, an aperture in said waste plug valve, means 25 for operating said waste plug valve, said operating means being shiftable laterally with respect to the center of said waste plug and extending into said aperture when said operating means lies substantially in line with a vertical 30 plane passing through the center of said waste plug valve and being removed from said aperture when said operating means is shifted laterally from said plane, and a groove extending between the base of said plug and said aperture. 35

3. A waste fitting comprising a waste plug valve, a groove in said waste plug valve, means for operating said waste plug valve, said operating means having a portion extending into said groove, and means in said groove for engaging 40 said operating means and preventing removal of said waste plug valve when said operating means is approximately in the same vertical plane as the center of said waste plug valve, said means being disengaged from said operating means 45 when shifted laterally from said plane.

4. A waste fitting comprising a waste plug valve, means for operating said waste plug valve, said operating means being movable laterally with respect to the center of said waste plug, 50 means in said waste plug valve for receiving said operating means, said receiving means being shaped to cause said operating means to lock said waste plug valve against removal when said operating means is approximately in a vertical 55 plane passing through the center of said waste plug valve and to permit removal of said waste plug valve when said operating means is shifted laterally from said plane.

5. A waste fitting comprising a waste plug 60 valve, means for operating said waste plug valve, said operating means being pivotally mounted to permit vertical and lateral movement thereof and engaging said waste plug valve and locking it against removal when said valve operating means 65 is in normal operative position and being disengageable from said waste plug valve by lateral movement of said operating means.

6. A waste fitting comprising a waste plug valve, means for operating said waste plug valve, 70 said operating means being pivotally mounted to permit vertical and lateral movement thereof and normally engaging and locking said waste plug valve against removal, the rotation of said waste plug valve causing said op- 75

- erating means to be pivoted laterally and to be disengaged from said valve.
7. In combination, a lavatory, a waste valve positioned therein, a housing formed integral with said lavatory, a bore in said housing, a shoulder in said bore, valve actuating means comprising a portion extending through said housing and engaging said valve, and a portion adapted to pivotally seat on said shoulder, packing interposed between said shoulder and said valve actuating means, and means for retaining said valve actuating means in said bore, said means comprising a slot in said housing extending through said bore, a nut positioned in said slot, a plug positioned in said bore, having threaded engagement with said nut and abutting said packing, and means in said plug for engaging said operating means.
8. In combination, a lavatory, a waste valve positioned therein, a housing attached to said lavatory, a bore in said housing, valve actuating means positioned in said bore and means for retaining said valve actuating means in said bore, said means comprising a slot in said housing extending through said bore, threaded means positioned in said slot and retaining means positioned in said bore, having threaded engagement with said threaded means and abutting said valve actuating means.
9. In combination, in a lavatory, a waste housing, a bore in said waste housing, a slot in said housing extending through said bore transversely thereof, retaining means for valve actuating mechanism positioned in said bore and threaded means of larger diameter than the diameter of said bore, positioned in said slot and having threaded engagement with said retaining means.
10. In a lavatory waste fitting, the combination of a supply fitting, a discharge spout provided with an escutcheon, a yoke attached to said supply fitting, an operating rod slidably mounted in said escutcheon, valve actuating means, a lift rod connected at one extremity to said valve actuating means and connecting means pivotally connected to said yoke, said operating rod and said lift rod.
11. In a lavatory waste fitting, the combination of a supply fitting comprising a discharge spout, a yoke attached to said supply fitting, an operating rod slidably mounted on said discharge spout, valve actuating means, a lift rod connected at one extremity to said valve actuating means, and connecting means pivotally connected to said yoke, said operating rod and said lift rod.
12. In a lavatory waste fitting, the combination of a supply fitting, an operating rod, valve actuating means, a lift rod connected to said valve actuating means and connecting means pivotally connected to said supply fitting, said operating rod and said lift rod.
13. A waste fitting comprising a waste plug valve, operating means for said valve, a groove in said valve, said operating means extending into said groove and said groove being formed with one side of a more gradual pitch than the other side whereby to permit rotation of said valve and lateral displacement of said operating means, and means in said groove for engaging said operating means and preventing removal of said waste plug valve when said operating means is approximately in the same vertical plane as the center of said waste plug valve, said means being disengaged from said operating means when said operating means is shifted laterally from said plane.
14. In combination in a plumbing fixture, a waste housing, a bore in said waste housing, valve actuating means positioned in said bore, means for retaining said valve actuating means in said bore, and means removably positioned in said bore for retaining said retaining means in said bore.

CARL J. KOHLER.
